UNITED STATES PATENT OFFICE.

WILLIAM LIDDELL, OF BROOKLYN, NEW YORK, ASSIGNOR TO CONTINENTAL PAPER BAG COMPANY, A CORPORATION OF MAINE.

PAPER-BAG MACHINE.

No. 814,006.

Specification of Letters Patent.

Patented Feb. 27, 1906.

Application filed September 2, 1904. Serial No. 223,149.

To all whom it may concern:

Be it known that I, WILLIAM LIDDELL, a citizen of the United States, and a resident of Brooklyn, in the county of Kings and State of New York, have invented certain new and useful Improvements in Paper-Bag Machines, of which the following is a specification.

This invention relates to paper-bag machines, and directly to that class of such machines as are provided with two cylinders or rolls between and on which one end of a paper tube having an inwardly-folded tuck in each side thereof is opened out and folded down into the well-known diamond form.

15 In the drawings accompanying this specification, Figure 1 represents a plan view, with some of the parts broken away, of a part of a paper-bag machine, illustrating one form of my improvements. Fig. 2 is a side elevation, 20 partly in section, on line *a a* of Fig. 1 of the same. Fig. 3 is a plan view, partly in section, of a modified form of side clips and their operative mechanism. Fig. 4 is an end elevation, partly in section, corresponding to 25 Fig. 3. Fig. 5 is a side elevation, partly in section, illustrating the operation of the supplemental front finger. Fig. 6 is a front elevation of the means provided for stripping the diamond-folded blank from the paste- 30 segment. Fig. 7 is a side elevation, partly in section, of the same and illustrating its operation. Fig. 8 is a detail elevation showing one of the side clips closed.

In the present embodiment of my improvements I have shown only such parts of a paper-bag machine as are necessary to suitably illustrate my improvements, and there- 35 in 2 3 represent a pair of feed-rolls suitably mounted, preferably one above the other, on 40 shafts 18 19, respectively, and revolvably sup- ported in uprights 4 5 fixed on main frames 6 7, respectively. Roll 2 is provided with a 45 creaser-blade 87 and roll 3 with a correspond- ing creaser-groove 88 for forming the main transverse crease in the bag-blank as said blank is fed between the rolls. Said creasing means are for convenience placed on rolls 2 3; but they could with equal efficiency be placed on rolls 10 11. Said rolls 2 3 are provided to 50 feed the bag-blanks to the folding cylinders or rolls 10 11, which rolls are suitably supported, preferably one above the other, on shafts 20 21, respectively, revolvably support-

ed in uprights 8 9. Said uprights are fixed on main frames 6 7, respectively, and at a 55 suitable distance in advance of feed-rolls 2 3. Between rolls 2 3 and 10 11 a suitable table, as 111, is provided to assist the transfer of the bag-blanks from the feed-rolls to the folding-rolls.

60 Somewhat below and to the left of folding-roll 11, Fig. 2, and mounted for rolling contact therewith on shaft 22 in main frames 6 7 is ironing-roll 12. Still farther below is delivery-roll 13, mounted for rotation on shaft 65 23 in frames 6 7. To the left of said roll 13 is pasting and creasing segment 14 and below it is paste-transfer roll 15, both mounted on their respective shafts 24 25 in side frames 6 7. Folding or distending rolls 10 11, ironing- 70 roll 12, paste-segment 14, and paste-transfer roll 15 are preferably all of the same diameter, and delivery-roll 13 has preferably a diameter in multiple of the diameter of roll 10 or 11. In the present instance said roll 13 75 has twice the diameter of roll 10 or 11 and is provided with two folding-beds upon its periphery, as rolls 10 11 are designed to open out and deliver to the succeeding mechanism two paper-bag blanks for each revolution of 80 roll 13.

Paste may be supplied to transfer-roll 15 by some suitable means, such as paste-reservoir 16 and roll 17, which reservoir and roll may be supported by some convenient means. 85 (Not shown.)

The several rolls and segment just described may be caused to rotate with equal peripheral speeds in the directions of their respective arrows by means of suitable gearing 90 fast to their respective supporting-shafts, and which gearing is indicated in a general way by G in Fig. 1. As such gearing is of well-known character, further description thereof is deemed unnecessary. Power may be trans- 95 mitted to the projecting end of shaft 21, Fig. 1, and thence to the other parts of the machine.

Referring now more in detail to the means provided for forming the diamond fold, roll 100 11 has pivotally mounted in brackets, as 32, on each end thereof levers, as 27. At the free ends of said levers are pivotally mounted side clips, as 29. Said levers are urged toward their outer positions, respectively, away 105 from the roll by means of push-springs, as 31.

- On each end of roll 11 and projecting outwardly therefrom in the line of its axis and contiguous to their respective side clips are brackets, as 35. Said brackets are each provided with cam-slots, as 37, for engagement with cam-pins, as 39, on outwardly-extending portions of side clips 29 29, respectively. Cam-slots 37 are so shaped and disposed in their respective brackets 35 that when by the hereinafter-described means arms 27, Fig. 2, are moved inwardly toward roll 11 the blank-engaging noses, as 40, Fig. 1, of side clips 29 are caused to move toward, over, and then down onto the face of said roll 11 or onto any bag-blank suitably disposed on the face of said roll. Also when levers 27 are allowed to swing outwardly away from roll 11 urged by their respective springs 31 said noses 40 of side clips 29 will be moved upwardly and backwardly from the face of roll 11 and then downwardly below the level of the face thereof.
- Levers 27 may be moved inwardly by the following means: On upwardly-extending brackets 44 44, fast to a beam 46, which beam is in turn supported by main frames 6 7, respectively, are cams 43 43. Outwardly extending from each of levers 27 and preferably relatively near the pivots thereof are arms carrying cam-rolls 47 47, respectively, for engagement with cams 43 43. To assist levers 27 27 to vibrate always in one plane with respect to roll 11, guide-brackets 49 49 are secured to opposite ends, respectively, of said roll for engagement with said levers, respectively.
- For clamping the lower ply of the mouth of the bag-blank to lower roll 11 the usual front clip, as 51, is provided. Said clip is secured to pivot-shaft 52, with which it is oscillated in proper time to grip the bag-blank to the roll, by means of arm 53 on said shaft, and which arm carries roll 54 thereon for engagement with still cam 55 in reaching from upright 8. Said front clip 51 may be lifted from engagement with the bag-blank or roll-face by means of spring 56, coiled about the outboard portion of shaft 52, one end of the spring being secured to roll 11 and the other end to arm 53.
- Roll 10 is provided with side clips 28, similar to side clips 29 of roll 11, and operated by similar means, such as levers 26, having rolls 48 and guided by brackets 50, cams 42 and 34, cams 34 having slots 36, &c., respectively, except that cams 42 have shorter working faces than cams 43, respectively, as it is necessary that the side clips of roll 10 release their grip on the bag-blank before the side clips of roll 11 release their grip thereon.
- In lieu of a front clip similar to front clip 51 of roll 11 roll 10 is provided with one or more needles, as 57, projecting from its face, and which are adapted to penetrate both the upper and lower plies of the bag-blank as that part of said roll bearing the needle or needles rolls into contact with the blank. As the forward end of the blank passes out from the bite of rolls 10 11 front clip 51 in roll 11 strips off the lower ply of the blank from said needles, which needles retain their hold on the upper 70 ply of the blank and lead it upwardly around roll 10, Fig. 5. Roll 11 may be provided with suitable cavities, as 58, into which said needles 57 may pass uninjured as the rolls roll together. A suitable plow, as 59, Fig. 2, 75 depending from cross-bar 60, is provided to strip the upper ply of the bag-blank from the needles at the proper time. Said plow is preferably provided with horns 61, projecting into grooves 62 in roll 10, whereby said 80 horns are insured access under the advancing edge of the upper ply of the blank.
- An alternate construction of the side-clip mechanism is shown, Figs. 3 and 4. The section of the major part of Fig. 3 is taken on line d d of Fig. 4; but the section through the bearings of that figure is taken on line c c of said Fig. 4. The section of Fig. 4 is taken on line b b of Fig. 3, and a portion of the upper part of roll 10 is broken away to better show 85 cams 440 and 68. In Figs. 3 and 4 each pair of side-clip levers, as 270 270, are pivotally mounted in opposite ends of a bar, as 63, which bar is mounted for approximately radial reciprocation in a slot, as 70, in one side 90 of roll 1100. By these means side clips 290 290, fast to the free ends of levers 270 270, respectively, may be moved from below the level of the face of said roll to a position 95 slightly above said face and then after being 100 thrust inwardly over said roll-face may be lowered toward said face to grip the lower plies of a bag-blank thereon. The means provided to accomplish these movements are as follows: Projecting inwardly from side frames 6 105 7 are cams, as 64, for engaging horns 65, projecting from the ends, respectively, of bar 63. As said horns ride up the inclines at the forward ends, respectively, of cams 64 64 bar 63 will be moved inwardly toward the center of 110 roll 1100, and side clips 290 will thus be raised above the level of the face of said roll.
- On outwardly-projecting arms 67 67 on levers 270 270, respectively, are mounted for rotation cam-rolls, as 47. Said rolls engage 115 cams 430 430, extending inwardly from uprights 6 7, respectively, and by which cams said rolls, and therefore side clips 290 290, are thrust inwardly just after said clips have been raised above the level of the face of roll 1100. Immediately thereafter horns 65 65 pass into depressions, as 69, in cams 64 64, whereby side clips 290 290 are lowered toward the face of said roll. In practice said successive upward, inward, and downward 120 movements of the side clips may overlap more or less, whereby more time may be afforded each movement. Horns 65 65 and rolls 47 47 may be urged toward their respective cams and levers 270 270 urged to their 125 130

outer positions, respectively, by means of springs, as 71, which act against projecting ears, as 72, provided therefor on said arms. Said springs are coiled around steady-posts, 5 as 73, projecting from the ends of the roll, and the other ends of said springs thrust against posts, as 74, also projecting from the ends, respectively, of said roll. Guides, as 49, are provided on roll 1100 to assist levers 10 270 270 to travel in one plane as to said roll. Upper roll 1000 is provided with side clips, as 280, mounted and actuated in all ways similar to the side clips of roll 1100, except that cams 68 are shorter than cams 64, so as to 15 cause the side clips of upper roll 1000 to open before the side clips of lower roll 1100.

Ironing-roll 12 is provided with a supplemental front finger 75, pivoted at 77 at or near the periphery of said roll and arranged 20 and adapted to swing outwardly from said roll and impinge against that part of the forward end of the lower ply of the bag-blank on roll 11 where the paper is to be turned over for forming the forward end of the diamond fold. In the present instance the bag-blank is shown as having slits in the forward end thereof whereby the diamond fold is commenced a short distance back from the front edge of the blank, Fig. 5. Roll 12 may, if 25 desired, be considered simply as a carrier for the supplemental front finger, as the ironing that is done by said roll could be done by other means. Finger 75 is provided with a T-head 76, whose width corresponds with the 30 width of front flap 78 of the bag-blank or with the desired width of separation of the turned-over portions of the forward end of the diamond fold. Finger 75 is moved outwardly for engagement with roll 11 or with a 35 bag-blank thereon by means of spring 79, coiled about the projecting end of pivot-shaft 77. One end of said spring is secured to roll 12 and the other end to collar 80, fast on the outer end of said shaft. The opposite end of 40 said shaft 77 is provided with an arm 81, bearing a roll 82 for engagement with still cam 83. Said cam is supported on sleeve 84, projecting inwardly about shaft 22 from frame 7. Said cam, through roll 82, arm 81, and shaft 45 77, controls the outward movement of arm 75 and at the proper time retracts said arm to its inoperative position, Fig. 2. Said spring 79 is also effective to urge roll 82 against cam 83. Shaft 22 of roll 12 is in two 50 parts, said parts having a space between their inner ends, respectively, Fig. 1, so that finger 75 may swing across the center of roll 12, Fig. 5, without interference; also, roll 11 is provided with a groove 86 to allow shaft 77 55 in roll 12 to pass roll 11 without interference.

On a rod 840, supported in side frames 6 7, is deflector 85 for bending downwardly the forward end of the diamond-folded blank as it emerges from between rolls 11 and 12 and 60 directing it into the bite of rolls 12 and 13.

Said deflector may consist of two comparatively narrow plates 85 85, Fig. 1, so disposed as to allow the free passage of the flattened portions of shaft 77.

Each of the two folding-beds 95 96 of roll 70 13 may be provided with one or more pairs of oppositely-disposed side clips, one of said side clips being shown at 89, Fig. 2. Said clips may be of some well-known construction—as, for instance, a blade or clip 90, mounted on one end of an outwardly-extending arm having a roll 91 at the other end thereof for engagement with the usual actuating-cam. (Not shown.) Said arm is pivotally supported for oscillation at 92 below 80 the surface of the folding-bed 95. Folding-bed 96 may also be provided with side clips similar to those on folding-bed 95. The location of these clips in relation to their respective folding-beds is such that each oppositely-disposed pair may be actuated to grip a bag-blank suitably disposed on their respective folding-bed directly in advance of the place where the rear flap folding crease is to be made. No such clips or, as for that 90 matter, any clips are necessary on roll 13 for the practice of my invention, and the present clips are herein supplied as adjuncts to the later operations of folding the rear and front flaps, but which foldings are no part of my 95 present improvements, and therefore no means are provided therefor.

Folding-bed 95 is provided with two grooves 97 98, and folding-bed 96 is provided with two grooves 99 100 for coaction with creaser-blades 101 102, respectively, of paster and creaser segment 14. Roll 13 is also provided with grooves 103 104 similar to groove 86 in roll 11 to allow the passage of shaft 77 in roll 12. 105

Between roll 12 and segment 14 is provided another deflector 94 similar and similarly mounted to deflector 85 for the purpose of directing the leading flap of the diamond-folded bag-blank on roll 13 under segment 14. 110

Creaser and paster segment 14 is provided with the usual paste-applying surfaces 103 and the usual creasing-blades 101 102 for defining the positions respectively at which the rear and front flaps of the bag-blank are to be 115 folded over.

The tendency of the forward end of the diamond-folded blank to cling to the paste-segment is in the present instance counteracted by the following means. Pivotaly mounted 120 at 104 in segment 14 is a rearwardly-reaching stripping-finger 105. Said finger is normally disposed in a cavity in and below the surface of said segment and preferably extends rearwardly of creaser 102, said creaser having a cavity 106 therein for the reception of said finger. Finger 105 is preferably made of wire and coiled one or more times about its shaft 104 and has the coiled end thereof fixed to said shaft. By means of said coils the fin- 125 130

ger is allowed to yield a certain amount, whereby its action is rendered less harsh. On that end of pivot-shaft 104 extending toward the right hand in Fig. 6 is fixed arm 107, bearing at its outer end roll 108 for engagement with cam 109. Said cam is fixed to the inner end of sleeve 110, and the outer end of said sleeve is fixed to frame 6. Shaft 24 passes through said sleeve and cam and revolves therein. The contour of cam 109 is such that as segment 14 turns in the direction of its arrow, Fig. 7, at the proper time roll 108 rides up onto the high part of said cam and arm 107, and consequently finger 105 is moved outwardly, said finger passing without the periphery of segment 14 and pressing away therefrom any bag-blank adhering thereto, Fig. 7. Said stripping-finger is also efficient to counteract any tendency 20 of the bag-blank to cling to creaser-blade 102 after said blade has performed its function.

The operation of my improved machine is as follows: The paper-bag blanks which I preferably use are of the well-known tubular form, having an inwardly-folded tuck in each side thereof and having the forward ends of the lower plies, respectively, projecting slightly in advance of the upper plies thereof and having each of said lower plies provided 30 with two slits of proper depth from the bases of which slits the front flap of the diamond fold springs. The forward end of a suitable blank, as B, being now presented to the bite of feed-rolls 2-3, Fig. 2, the machine is started and the bag-blank is fed forward into engagement with creaser-blade 87 and creaser-groove 88 in said rolls, respectively, and thence onward to distending-rolls 10-11, where the forward end of the lower ply of the 40 blank is delivered under the now open front finger 51 in roll 11. Said front finger then closes down onto the lower ply of the blank and grips it to the periphery of the roll, Fig. 2. Closely following this operation needles 57 roll onto and penetrate the blank. By the continued forward movement of the rolls the lower ply of the blank is led downwardly on roll 11 by clip 51, whereby said lower ply is stripped from needles 57. Said needles, 50 however, retain their hold on the upper ply of the blank and lead it upwardly on roll 10. The resultant distending of the side tucks of the blank affords a free entrance for the side clips, which by means of their respective 55 cams pass upwardly, inwardly, and downwardly onto the respective plies of the side tucks, thereby gripping them to the faces of rolls 10 and 11, respectively. This side-clip-gripping operation occurs just as near the 60 plane passing through the axes of rolls 10-11 as possible, so as to insure early control of the diamond folding. During this time ironing-roll 12 has been revolving in the direction of its arrow and supplemental front finger 75

has been moving outwardly therein, and as 65 the several parts of the mechanism reach the positions of Fig. 5 front clip 51 has released its hold on the bag-blank and supplemental front finger 75 has engaged therewith with its T-head 76 disposed between the ends of the 70 slits in the bag-blank. Directly following this step in the operation it is sometimes desirable to employ an ironing-plate or ironing-wings to flatten down and finish the diamond fold; but as such means are not a part of my 75 invention nor necessary thereto I have omitted them herein. The continued revolution of rolls 10-11 continues the distension and folding down of the diamond fold into approximate flatness when the side clips of 80 roll 10 release their hold and withdraw and the rear flap of the diamond fold is released from needles 57 by stripper 59. The then substantially folded diamond-folded blank still retained on roll 11 by means of finger 75 85 and side clips 29 passes under ironing-roll 12, whereby the diamond fold is rolled down and flattened. Finger 75 is then withdrawn from the front flap and is retracted to its normal position in ironing-roll 12. The bag-blank now passes over deflector 85, by which 90 said blank is directed onto folding-bed 96 of roll 13 and into the bite of rolls 12 and 13. Said blank then passes onward under deflector 94 and under paster and creaser segment 14. 95 If side clips are employed on the folding-beds of roll 13, those of folding-bed 96 close immediately after passing roll 12, Fig. 7, at which time creaser 102 has just completed its operation. Shortly before this time finger 105 100 commences its outward movement and pressing the forward end of the bag-blank before it strips it from the paste-segment, as shown in Fig. 7. Segment 14 continues its rotation in coacting with roll 13 until creaser 105 105 101 engages and creases the bag-blank. The diamond-folded and creased bag-blank may now be discharged from the machine or retained on folding-bed 96 of roll 13 by means of side clips 93 and conveyed thereby to some 110 suitable means (not shown) for folding the end flaps and completing the bag.

I claim—

1. The combination of a folding-roll, a lever substantially radial to the roll pivoted at 115 each end of the roll, a side clip mounted in the free end of each lever, means for oscillating the levers toward and away from the roll and means for raising and lowering said levers in the plane of their length all combined 120 and operating together substantially as described.

2. The combination of a pair of distending-rolls, side clips oppositely disposed on opposite ends of each thereof respectively, means 125 for moving the side clips into and out of engagement with their respective rolls and means for retracting said side clips radially

- to positions below the faces of the rolls respectively, all combined and operating together substantially as described. 50
3. The combination of a roll, a lever, pivotally mounted at each end thereof, a side clip mounted in the free end of each lever, means to oscillate the levers lengthwise of the rolls and means to raise and lower the side clips both in their inward and outward 55 positions substantially radially of the rolls, all combined and operating together substantially as described.
4. The combination of a pair of distending-rolls, means for holding the upper and lower 15 plies of the forward end of a bag-blank thereto respectively, a lever substantially radial to its respective roll, pivotally mounted at each end of each of said rolls, a side clip, mounted in the free end of each of said levers, 20 means to oscillate the levers longitudinally of the rolls and means to raise and lower the side clips substantially radially of the rolls respectively, all combined and operating together substantially as described. 60
5. The combination of a roll, a bar 63 therein, reciprocatable inwardly and outwardly with respect of the periphery of the roll, cams 64 for reciprocating the bar, a lever 270 pivotally mounted in each end of the bar, 25 a side clip 290 carried by each lever and cams 43 for oscillating the levers toward and from the roll, all combined and operating together substantially as described. 70
6. The combination of a folding-roll, side 35 clips mounted on said roll for reciprocation approximately radial thereto, means to reciprocate the side clips, and means for moving said side clips longitudinally of said roll in a plane radial thereto in coaction with said reciprocation, all combined and operating together substantially as described. 80
7. The combination of a folding-roll, side 40 clips and a front clip thereon, a revolute carrier 12, a supplemental front finger pivotally 45 mounted in said carrier, means for revolving the carrier in time with the roll and for swinging said finger inwardly and outwardly of said carrier for coöperation with the folding- roll, all combined and operating together substantially as described. 85
8. The combination of a folding-roll, side 50 clips and a front clip thereon, ironing-roll 12, supplemental front finger 75 pivoted therein, means, comprising arm 81 and cam 83 for swinging said finger inwardly and outwardly 55 of the ironing-roll for coöperation with the folding-roll, and means for timing the ironing-roll with the folding-roll, all combined and operating together substantially as described. 60
9. The combination of a distending-cylinder, means to grip a bag-blank thereto a rotatable carrier adjacent to the distending-cylinder, a supplemental front finger eccentrically pivoted in the rotatable carrier, 65 means for operating said finger for engagement with the bag-blank to prevent tearing in forming the diamond fold, all combined and operating together substantially as described. 70
10. The combination of a revolute folding-bed 96, means for holding a bag-blank thereon, a revolute pasting-wheel 14, a stripping-finger 105 mounted in said wheel for movement inwardly and outwardly thereof for coaction with the folding-bed, means to actuate the stripping-finger and means for timing the pasting-wheel and the folding-bed, all combined and operating together substantially as described. 75
11. The combination of a folding-roll, a lever substantially radial to the roll pivoted at each end of the roll, a side clip in the free end of each lever, means for oscillating the levers toward and away from the roll and means 85 for raising and lowering the side clips radial to the roll all combined and operating together substantially as described. 85

Signed this 31st day of August, 1904, at Rumford Falls, Maine, in the presence of two 90 subscribing witnesses.

WILLIAM LIDDELL.
